UNITED STATES PATENT OFFICE.

LEON W. BROWN, OF NEW YORK, N. Y., AND PETER A. RASMUS, OF PAXTON, ILLINOIS.

TURN-TABLE.

1,112,673.

Specification of Letters Patent.

Patented Oct. 6, 1914.

Application filed July 16, 1914. Serial No. 851,397.

To all whom it may concern:

Be it known that we, LEON W. BROWN, a citizen of the United States, residing at New York, in the county of New York and State of New York, and PETER A. RASMUS, a citizen of the United States, residing at Paxton, in the county of Ford and State of Illinois, have invented certain new and useful Improvements in Turn-Tables; and we do declare the following to be a full, clear, and exact description of the invention, such as will enable others skilled in the art to which it appertains to make and use the same.

This invention relates to new and useful improvements in turn tables for automobiles and more particularly to a device which will enable an automobile to be turned in a limited space in a garage.

A further object of the invention resides in providing a device which derives its power from the wheels of an automobile when the latter is properly positioned thereon.

Still another object of the invention resides in providing an improved means for locking the table against movement at predetermined points in the rotation thereof.

A still further object resides in providing a device which is simple and durable in construction, inexpensive to manufacture and one which will be very efficient and useful in operation.

With these and other objects in view, our invention consists in the novel features of construction, combination and arrangement of parts as will be hereinafter referred to and particularly pointed out in the specification and claims.

In the accompanying drawings forming a part of this application:—Figure 1 is a plan view of a device constructed in accordance with our invention, parts being broken away and parts being disclosed in section. Fig. 2 is a vertical section therethrough as seen on line 2—2, Fig. 1. Fig. 3 is a bottom plan view of the device, and Fig. 4 is a fragmentary view similar to Fig. 1 with parts being broken away and parts in section, the turn table being disposed to an operated and opposite position to that shown in Fig. 1.

In describing the invention we shall refer to the drawings in which similar reference characters designate corresponding parts throughout the several views and in which—

55 1 indicates the floor or base of a garage of the public or private type, said floor being

provided at a predetermined point therein with a pit or cavity 2 and mounted in the base or floor of said pit or cavity is a base plate 3. This base plate has a track 4 provided in the upper face thereof the same being annular and arranged at a point adjacent the peripheral edge of said base plate and mounted on said base plate centrally thereof is a bearing pin 5, the purpose of which will be hereinafter and more particularly set forth. Mounted for rotation on said base plate 3 is a table 6 which forms the turn table proper the same being of disk-like formation having a central opening therein through which is received the upper portion of said bearing pin 5. This table 6 is provided with a depending flange 7 which entirely surrounds the same and is received in the pit or cavity 2 and in order for this table 6 to be rotated within the pit and on said base plate, a plurality of rollers 8 are provided. These rollers 8 are rotatably mounted on stub shafts 9 carried on the flange 7. These stub shafts project inwardly from the flange and are arranged thereon at predetermined points and these rollers so position the table 6 as to permit the same to fit flush with the floor or base 1 of the structure. An additional shaft 10 is provided the same having one end thereof mounted in said flange 7 and the opposite end which projects inwardly with respect to the flange to be mounted in a bearing plate 11. Rotatably mounted on this shaft is a friction or drive roller 12 which engages the surface of a track way 4 in the base plate to cause said table 6 to be rotated at certain times, as will be hereinafter more particularly set forth. This last mentioned roller 12, however, as well as the rollers 8 are received in the same track way 4 so as to properly position said table 6 in the pit.

Secured on the underface of the table 6 and arranged in parallel relation to one another is a pair of angle bars 13 which are longitudinally slotted as at 13' to adjustably receive pairs of shafts 14, the latter being rotatably supported in adjustable bearing plates 14' which are secured to the bars 13 by bolts 14" passing therethrough and through the slots 13'. A pair of shafts 14 is provided adjacent each end of the angle bars 13, the shafts of each pair being spaced one from the other and having peripherally grooved and serrated rollers 15 mounted on the ends thereof. These rollers 15 are of

the friction type, being formed of any desired material, and in view of the particular arrangement of the shaft and the fact that each shaft is provided with a pair of said rollers it will be seen that said rollers are arranged in pairs on the table. The table 6 is provided with pairs of openings 16, the same receiving therethrough portions of the pairs of friction rollers 15 carried on the shafts 14, thus enabling said rollers and shafts to be rotated by objects received on said table and engaging said rollers.

Mounted on shafts 14 are sprockets 17 said sprockets being arranged in longitudinal alinement and extending over said sprockets for engagement with the teeth thereof is an endless chain 18, whereby said shafts may all be rotated in the same direction, when said rollers 15 are rotated. The upper reach of the chain 18 is held in engagement with the teeth of the sprocket 17 by having contact with the underface of the table 6 and we have provided a bracket 19 on one of the bars 13 which bracket has a roller 20 on the outer end thereof, engaging the lower reach of said chain 18. This roller 20 retains said lower reach in engagement with the teeth of the sprocket 17 and thus a positive connection is had between all of the shafts.

The pairs of shafts 14 are arranged in a plane above the plane of the drive shaft 10 carrying the friction roller 12 and means is provided for driving said shaft 10 from one of said shafts 14. To this end a worm 21 is provided on one of said shafts 14 adjacent the inner end of said shaft 10. A pinion 22 is carried on the shaft 10 for engagement with the worm and thus it will be seen that upon rotation of said shafts 14, the shaft 10 will be also rotated to cause the friction roller to be rotated for engagement with the track way 4. Thus said turn table will be caused to rotate on the base plate 3.

As stated above, the rotation of the shaft 14 will cause said turn table to be rotated on the base plate and we have provided a means for stopping the rotation of said table at predetermined points in the rotation thereof. To this end we provide a sleeve 22 on the outer shaft 14 opposite that having the worm thereon. This sleeve has teeth or the like 24 formed in the peripheral edges thereof which are designed for engagement with pins or studs 25 provided on said shaft at points beyond each end of said sleeve. This construction forms a clutch mechanism whereby when said sleeve is disposed in one direction the one end thereof will engage the one pin 25 whereas when said sleeve is disposed in the opposite direction the other pin or stud 25 will be engaged by the opposite end of said sleeve.

Mounted on the underface of the table 6 is to depend therefrom is a stud 26 which has

fulcrumed thereon an angular lever 27, the fulcrum point being disposed intermediate the ends of said lever. The inner end of said lever 27 has loose connection, through the medium of a pin and slot, with said sleeve or clutch member 23 and the outer end of said lever which projects through a slot 28 in the flange 7 is adapted for engagement with a pair of stop members 29 which are arranged at diametrically opposite points on the base plate 3. The outer end of said lever 27 is off-set as shown at 30 whereby to be readily engaged with said stop member 29 as will be seen. In the rotation of said turn table, said lever will engage said stop members whereby to cause said clutch member to be disposed to engaging position and thus prevent the rotation of the shafts 14 and correspondingly stop the rotation of said turn table in the pit.

Mounted on the upper face of the table 6 at points diametrically opposed to one another are the guide tracks 31 which enable an automobile to be properly guided on the device. It will be understood that when an automobile is guided onto this table 6 between the track ways, each wheel of the machine will be received on a pair of friction rollers indicated in the drawing as 15 so that when the wheels of the automobile are rotated the device will be set in motion.

In operation assuming that a machine has been properly positioned on the turn table should it be desired to rotate said table so as to position said machine for exit from the garage and assuming that the space in said garage is too small to enable said automobile to be turned as usual, it is only necessary to place the machine in gear so as to cause the wheels thereof to be rotated. Each wheel of the automobile, as stated above, is received on a pair of friction rollers 15 so that when said wheels are set in rotation, the rollers will be rotated on the device and prevent the automobile from moving forwardly. The rotation of said rollers 15, however, will cause the shafts 14 to be rotated and the friction roller 12 engaging the track 4 will cause the complete table with the automobile thereon to be rotated. A pair of stop members 29 being provided at points diametrically opposite one another on the base plate, it will be seen that this turn table may only be rotated in an arc of 180 degrees. In rotating to this degree, it will be seen that the outer end of the angular lever 27 will engage one of said stop members and cause said clutch member to be effectively disposed thus locking said shaft 14 against rotation and preventing the rotation of said rollers 15. The shafts 14, carrying the rollers 15, however, are allowed to rotate while the table is turning, coil springs 27 being employed to retain the levers 27 in neutral position.

As soon as the rollers 15 are engaged by the outer end of the angular lever 27, the coil springs 27 will cause the levers 27 to move into the engaging position and thus lock the shaft 14 against rotation. The automobile will then be turned in the direction of the track 4 and when the outer end of the angular lever 27 has engaged the stop member 29, the coil spring 27 will cause the lever 27 to move into the neutral position and thus release the shaft 14 so that the automobile may be turned in the direction of the track 4.

stop rotating, it will be seen that the wheels of the automobile will find a rigid surface for engagement therewith, thus causing the machine to be propelled forwardly, but inasmuch as the device has been entirely reversed in position the desired result has been accomplished. When one machine has left the turn table, it will be seen that the same is in position to receive another and the same will be automatic in its operation at all times, deriving its power entirely from the rotation of the wheels of the automobile on said device.

It may be here explained that the adjustable bearings herein described are employed for the purpose of rendering the device adjustable for cars having different wheel bases.

From the foregoing it will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to, within the scope of the appended claims, without departing from the spirit or sacrificing any of the principles of the invention.

Having thus described our invention what we claim is:

1. The combination with a turn table; of means operative by the wheels of a motor driven vehicle to cause rotation of said turn table, a double acting locking clutch in connection therewith and means for disposing said clutch to its effective position at predetermined points in the rotation of said turn table.

2. The combination with a turn table, pairs of parallel shafts mounted for rotation thereon, rollers on said shafts adapted to be engaged and rotated by the wheels of a motor driven vehicle on said turn table, and means in connection therewith to rotate said turn table upon the rotation of said shaft; of a double acting locking clutch on one of said shafts, an actuating lever for said clutch projecting beyond the peripheral edge of said table, and means adapted for engagement with said lever at predetermined points in the rotation of said turn table to lock the latter against rotation.

3. The combination with a pit, a turn table operatively mounted therein, pairs of parallel shafts rotatably mounted on said turn table, rollers on said shafts adapted to be engaged and rotated by the wheels of a motor driven vehicle on said turn table, means in connection therewith to rotate said turn table upon the rotation of said rollers and shafts, a double acting locking clutch on one of said shafts, an actuating lever for said clutch projecting beyond the peripheral edge

of said table, and a pair of stops stationarily mounted in the pit at diametrically opposite points therein, said stops being adapted for engagement with said lever to lock said turn table against rotation at predetermined points in said pit.

4. The combination with a pit, a turn table rotatably mounted therein, a pair of parallel shafts rotatably mounted on said turn table, rollers carried on said shafts adapted to be engaged and rotated by wheels of a motor driven vehicle on said turn table, and means in connection therewith to rotate said turn table upon the rotation of said rollers and shafts, of a double acting locking clutch on one of said shafts, an angular lever fulcrumed intermediate of its ends on said turn table and having connection at one of its ends with said clutch member to actuate the latter, the opposite end of said lever projecting beyond the peripheral edge of said turn table, and a pair of stop members stationarily mounted in said pit at diametrically opposite points therein and arranged in the path of said actuating lever whereby to be engaged by the latter and lock said turn table against rotation in the pit at predetermined points.

5. The combination with a pit, a turn table operatively mounted therein, pairs of parallel shafts mounted for rotation on said turn table, rollers carried on said shafts adapted to be engaged and rotated by the wheels of a motor driven vehicle on said turn table, and means in connection therewith to rotate said turn table upon the rotation of said rollers and shafts; of a sleeve like locking member loosely mounted on one of said shafts and having teeth at the ends thereof, studs mounted on said last mentioned shaft beyond the ends of said sleeves adapted for engagement with the teeth on the latter when said sleeve is slid on said shaft, an angular lever fulcrumed intermediate of its ends on said turn table and having its inner end loosely engaged with said sleeve member to actuate the latter, the opposite end of said lever projecting beyond the peripheral edge of said turn table, and a pair of stop members rigidly mounted in said pit at diametrically opposite points therein adapted for engagement with the last mentioned end of said lever to lock said turn table against rotation at predetermined points.

6. In a turn table of the class described, a pit, a platform mounted for rotation therein, said platform being provided with pairs of openings, pairs of shafts rotatably mounted on the under side of said platform, friction rollers carried on said shafts and projecting partially through the aforesaid openings in said platform, sprockets mounted on said shafts and arranged in longitudinal alignment thereon, an endless chain engaged with

said sprocket to rotate the same and the shafts in unison, means in connection with one of said shafts for rotating the turn table in the pit upon the rotation of said shaft, and additional means in connection with another of said shafts for locking said turn table against rotation at predetermined points in the pit.

7. The combination with a turn table, 10 pairs of parallel shafts adjustably mounted for rotation thereon, rollers on said shafts adapted to be engaged and rotated by the wheels of a motor driven vehicle on said turn table, and means in connection therewith to rotate said turn table upon the rotation of said shaft; of a double acting locking clutch on one of said shafts, an actuating lever for said clutch projecting beyond the

peripheral edge of said table, and means adapted for engagement with said lever at 20 predetermined points in the rotation of said turn table to lock the latter against rotation.

In testimony whereof we have hereunto set our hands in presence of two subscribing witnesses.
